UNITED STATES PATENT OFFICE.

FRANCESCO CIRELLI, OF PHILADELPHIA, PENNSYLVANIA.

SOUND-REPRODUCING MACHINE.

Application filed May 24, 1921. Serial No. 472,206.

To all whom it may concern:

Be it known that I, FRANCESCO CIRELLI, a subject of the King of Italy, residing at Philadelphia, in the county of Philadelphia 5 and State of Pennsylvania, have invented certain new and useful Improvements in Sound-Reproducing Machines, of which the following is a specification.

One object of my invention is to provide 10 in a sound reproducing machine an improved structure which will modulate the character of sounds reproduced from records in such manner as to improve and cause them to have a more natural quality.

Another object is to provide improved 15 means which is readily adjustable for varying the modulating effect so that the sound can be modulated in a manner best suitable to the natural quality of a voice which is being reproduced or to the natural quality of instruments which are being reproduced.

A further object is to provide an improved structure in which the sound conducting means includes sections pivoted 20 together so as to be folded one upon the other and locked in their folded positions so that they will be held against accidental movement; said sections when thus folded being readily removable as a unit and being 25 adapted so as to be stored in the case or cabinet of the machine.

A further object is to arrange the parts 30 of my invention so that they can be readily manufactured.

These objects, and other advantageous ends which will be described hereinafter, I attain in the following manner, reference being had to the accompanying drawings in which—

Figure 1 is a top plan view showing a machine made in accordance with my invention and illustrating the parts in their playing positions,

Figure 2 is a side elevation of Figure 1,

Figure 3 is a fragmentary elevation looking in the direction of the arrow α in Figure 1 and illustrating the sound box-carrying section of the sound conducting means in a position which it assumes when being moved into or out of playing position,

Figure 4 is a view of the same general character as Figure 3 showing the sound conducting sections folded and locked in their folded positions,

Figure 5 is a top plan view of Figure 4, and

Figure 6 is an enlarged section taken on the line 6—6 of Figure 1.

Referring to the drawings, 7 represents a box or cabinet which includes a hollow base 8 preferably made of a single piece of metal, such for example as aluminum. A hollow lid 9 is secured to the base 8 by a metallic hinge 10. The lid 9 is preferably made of a single piece of metal and of such shape 60 that when closed it will cover the top of the base 8; said base and lid having rounded corners as shown at 11.

I have illustrated the base 8 provided with two compartments 12 and 13 which are 70 produced by an upright transverse partition 14 and a top board 15. This top board includes a section 16 which is hinged at 17 and is positioned directly over the compartment 13. The compartment 12 serves to provide a space for a spring motor 18 which is diagrammatically represented and which can be wound by a crank 19 which is inserted through a collar 20 which is secured to the front of the base. The motor serves to rotate a center post 21 to which is connected a turntable 22; said turntable including a hinged section 23 which may be swung upwardly to permit access to the compartment 13 so that said compartment 13 can be used 85 for storing the sound conducting and transmitting means hereinafter described.

The enlarged surface of the flange 24 of the lid 9 has a pivot post 25 secured thereto so that when the lid is swung into an open 90 position as shown in Figures 1 to 4 inclusive, the post 25 will be upright. A horn 26 at its wide open end 27 has a socket 28 depending therefrom and adapted to be placed over the post 25 so that the horn will 95 freely swing in a horizontal plane on the post 25 as a pivot. From the end 27 the horn tapers forwardly and terminates in a transverse head 29; said head having a transverse cylindrical bore 30 which is open 100 at its opposite ends as shown in Figure 6. A sound conducting section 31 has a cylindrical sleeve portion 32 which is adapted to pivotally fit within the bore 30 as shown in Figure 6; said sleeve portion having a flange 33 adapted to abut one end of the head 29. The sleeve portion 32 has a hole 34 adapted to register with the interior of the horn and the free end 35 of said sleeve portion 32 is internally screw threaded to 105 receive the externally screw threaded stem 36 of a cap 37. The cap 37 is of a diameter

110

greater than that of the bore 30 so that the sleeve portion 32 will be pivotally retained within the bore 30.

In line with the sleeve portion 32 and directly adjacent the flange 33, the section 31 has an enlarged hollow portion 38 which provides an enlarged chamber 39. This portion 38 is preferably made spherical and has a flange 40 projecting outwardly therefrom 10 preferably in line with the sleeve portion 32 as shown in Figure 6. This flange 40 is internally screw threaded and an external screw threaded plug 41 is adapted to be screwed into the flange. The flange has 15 holes or perforations 42 extending entirely therethrough and spaced apart annularly; the arrangement being such that the plug 41 can be screwed into the flange 40 so as to either partially or entirely close the 20 perforations 42. The portion 38 has a tubular extension 43 which is arranged preferably at right angles to the axis of the sleeve portion 32. The forward end of the tubular portion 43 terminates preferably in an enlarged hollow knuckle 44 which provides an 25 enlarged chamber 45 as shown in Figure 5. A transverse tubular portion 46 of the section 31 projects from the knuckle 44 parallel with and substantially in the same direction 30 as that in which the sleeve portion 32 extends from the hollow portion 38. The outer end of the tubular portion 46 has a sound box 47 detachably secured thereto, which sound box may be of any suitable 35 construction providing means for engagement with the record mounted on the turntable 22, as shown in Figure 2. The tubular portion 46 is preferably provided with a knob or handle 48 to facilitate the swinging 40 of the sound conducting section 31 in the head 29 so that if desired to change a needle or to play another record the section 31 can be swung as shown in Figure 3 into a position such as shown in Figure 45 4 with the tubular portion 46 resting above the top of the horn 26.

I secure a small receptacle 49 on the top of the horn 46 in a position such as shown in Figures 1 and 2 and this receptacle can 50 be used for holding reproducing needles. A cover 50 is adapted to be detachably secured to the receptacle 49 as shown in Figure 4 after the section 31 has been swung upwardly and when it is desired to dis- 55 continue playing the machine, this cover has a part 50^a, as shown in Figures 4 and 5, that when secured to the receptacle it will serve as a stop for engagement with the tubular portion 46 so that the section 31 cannot 60 swing when the cover 50 is on the receptacle 49. When the cover 50 is removed from the receptacle however, the section 31 is free to swing and when resting on the horn 46 the needle chuck of the sound box 47 will be 65 in an upright position to permit the chang-

ing of the needle and the receptacle 49 is in a convenient position for the operator to secure a new needle and place it in the needle chuck.

I have found by actual experiments that by providing the sound conducting means with enlarged chambers in line with tubular extensions that the quality of the reproduced sound is superior to that produced when the enlarged chambers are not present. I have also found by actual experiment that by providing the flange 40 with the perforations and the plug 41 that by turning the plug to vary the amount of opening of said perforations that the quality of the sound produced is improved and furthermore that the sound can be modulated with the results above set forth in the objects of the invention. This improvement is particularly noticeable when the perforations are made adjacent the chamber 39.

When the parts are moved into the position as shown in Figure 4 and locked by the application of the cover 50 to the receptacle, the horn 26 can be lifted off the post 45 and readily stored in the compartment 13 merely by swinging the section 23 of the turntable and opening the hinged section 16 of the top board 15.

I have also found that by making the box or cabinet 7 with the base 8 and lid 9 of metal and connecting said lid and base with a metallic hinge that the sound waves emanating from the end 27 of the horn, when they engage the inner surface of the lid 9, will be amplified in a manner not previously accomplished and that the resulting sound is greatly improved.

When not desired for use, the crank 19 as well as the sound conducting means can be stored in the compartment 13 and the lid can be closed and secured by any suitable latch or locking means and I have provided a handle 51 on the cabinet so that it can be readily carried.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. In a sound reproducing machine, a sound conducting section, a second sound conducting section pivotally carried by said first named section, sound producing means carried by said last named section, and a receptacle provided with a cover having a portion for abutment with the last named section adapted to lock said section against

pivotal movement with the sound reproducing means raised out of operative position.

2. In a sound reproducing machine, sound conducting means including two sections pivotally connected together; means forming a support for one of said sections; a needle receptacle on said latter section; sound reproducing means on the other section, said latter section when raised being capable of moving over said needle receptacle; and a cover adapted to be secured to said needle receptacle, said cover having a

portion for abutment with said swung section to lock the sections against pivotal movement with respect to each other; substantially as described. 15

In testimony whereof I have signed my name to this specification in the presence of two subscribing witnesses.

FRANCESCO CIRELLI.
